UNITED STATES PATENT OFFICE.

GEORGE C. KINDT, OF JERSEY CITY, NEW JERSEY, ASSIGNOR TO GEO. BORGFELDT & CO., OF NEW YORK, N. Y., A CORPORATION OF NEW JERSEY.

DESIGN FOR A BOTTLE-RECEPTACLE.

47,564.

Specification for Design.

Patented July 13, 1915.

Application filed April 27, 1915. Serial No. 24,356. Term of patent 3½ years.

To all whom it may concern:

Be it known that I, GEORGE C. KINDT, a citizen of the United States, and resident of Jersey City, county of Hudson, and State of New Jersey, have invented a new, original, and ornamental Design for a Bottle-Receptacle, of which the following is a specification, reference being had to the accompanying drawing, forming a part thereof, and in which—

Figures 1 and 2 are perspective elevations, showing the bottle receptacle from points diametrically opposite one another.

I claim—

The ornamental design for a bottle receptacle, as shown.

GEORGE C. KINDT.
